(57) **CLAIM**

The ornamental design for a one-piece dish wand holder, as shown and described.

DESCRIPTION

FIG. 1 is a perspective view of the one-piece dish wand holder, according to a first embodiment;

FIG. 2 is a side view of the dish wand holder of FIG. 1;

FIG. 3 is a top view of the dish wand holder of FIG. 1;

FIG. 4 is a bottom view of the dish wand holder of FIG. 1;

FIG. 5 is a front view of the dish wand holder of FIG. 1;

FIG. 6 is a back view of the dish wand holder of FIG. 1;

FIG. 7 is a side view of the one-piece dish wand holder, according to a second embodiment;

FIG. 8 is a top view of the dish wand holder of FIG. 7;

FIG. 9 is a perspective view of the dish wand holder of FIG. 7;

FIG. 10 is a side view of a one-piece dish wand holder and dish wand assembly, according to a first embodiment;

FIG. 11 is a front view of the assembly of FIG. 10;

FIG. 12 is a side view of a one-piece dish wand holder and dish wand assembly, according to a second embodiment; and, FIG. 13 is a front view of the assembly of FIG. 12.

The one-piece dish wand holder straddles the dividing wall in a divided sink and supports a dish wand in an upright position.
